AIRFOIL MOUNTING AND ACTUATING
MECHANISM

Fredric E. Flader, Kenmore, N. Y., assignor to
Curtiss-Wright Corporation, a corporation of
Delaware

Application November 20, 1943, Serial No. 511,155

2 Claims. (Cl. 244—42)

1

This invention relates to improvements in mounting and actuating mechanisms for the auxiliary airfoils of airplanes, and more particularly the invention is concerned with a mechanism of the kind which may be availed of to extend and lower a flap, whereby to increase the effective camber of the wing of which the flap is a part and at the same time open a slot in, and increase the basic or overall area of, the wing.

One object of the invention is to provide a mechanism of the character generally described which will move the auxiliary airfoil rapidly to the desired position and which will support it solidly in such position.

A further object is to provide a mechanism which is operable to lower the auxiliary airfoil in any desired extended position.

A still further object is a mechanism which may, if desired, be actuated to lower the auxiliary airfoil without at the same time extending it.

A still further object is to provide a mechanism which may be utilized to mount the auxiliary airfoil upon the main airfoil without cutting into, or otherwise deforming, the nose or leading edge of the auxiliary airfoil.

A still further object is a novel design and arrangement of the parts of the mechanism, whereby to obtain simplicity in construction and dependability in operation.

The invention is illustrated in the accompanying drawing, in which:

Figure 1 is a view in plan of an airplane wing having a flap mounted and actuated by mechanism embodying the features of the invention.

Figure 2 is an enlarged transverse section taken along line 2—2 of Figure 1, the flap being shown in full lines in its normal elevated position and in dotted lines in its lowered, extended position.

Figure 3 is a similar section, the flap being shown in full lines in the same position as in Figure 2 but being shown in dotted lines in a lowered, non-extended position.

The mounting and actuating mechanism is illustrated by way of example in connection with a flap 10 of an airplane, the latter being sufficiently indicated for the purpose in view by a showing of a wing 11 thereof.

In accordance with the invention the flap 10 is connected to the main airfoil by an upper series of extensible arms 12 and a lower series of extensible arms 13. Although the said arms may, if desired, be in the form of jackscrews and mechanically actuated, they are preferably, as illustrated, hydraulically actuated. To this end, each of the arms 12 includes a cylinder 14 while each

2

of the arms 13 includes a cylinder 15. Hydraulic fluid from supply lines 16 and 17 may be introduced into the said cylinders through branches 18 and 19, respectively, the delivery of fluid under pressure from the pump, or other source, to the supply lines being controlled by a suitable valve or valves (not shown).

At its inner end each of the cylinders 14 is pivotally connected to a bracket 20 which is carried by a rib or other convenient part of the main airfoil. The cylinders 15, on the other hand, are secured at their outer as well as at their inner ends, as at 21, to fixed parts of the main airfoil. Plungers 22 which are connected to, or which are extensions of, the pistons (not shown) in the cylinders 14 are pivotally connected at their outer ends to ears 23 on upper and rearwardly located portions of the nose of the flap while plungers 24 associated with the cylinders 15 are connected at 20 their outer ends to ears 25 on lower and forwardly located portions of the nose of the flap, the connections of the plungers 22 with the ears 23 and the connections of the plungers 24 with the ears 25 preferably being along parallel lines. Normally 25 the plungers 22 and 24 support the flap in the full-line position shown in Figures 2 and 3. In such position the nose of the flap is located under, and in profile conforms substantially to, the trailing edge of the main airfoil, while the upper 30 and lower surfaces of the flap provide substantially uninterrupted continuations of the corresponding surfaces of the main airfoil.

The flap 10 may be extended and lowered to increase the lift of the wing by admitting hydraulic fluid into the cylinders 14 and 15, simultaneously or otherwise. As the plungers 22 and 24 are extended, the flap is moved to the dotted-line position illustrated in Figure 2. The movement of the flap to such position increases substantially the basic area, chord and camber of the wing and at the same time opens a slot between the nose of the flap and the trailing edge of the main airfoil through which air may flow from the under side of the wing. On the other hand, 40 if it is desired to maintain the basic area of the wing constant and obtain the increased lift by lowering the flap without extending it, hydraulic fluid may be admitted only to the cylinders 14. In this event the plungers 22 are extended while 45 the plungers 24 are held in their normal retracted positions, and the flap is moved to the dotted-line position shown in Figure 3 without opening a slot between it and the main airfoil. The flap may also be adjusted to, and supported 50 in, various other positions by limiting to differ-

ent degrees the outward movement of the plungers 22 and 24.

It will be apparent that the plungers 24 provide pivots about which the flap may be angularly adjusted by the plungers 22, the stationary cylinders 15 permitting rectilinear movement only of the plungers 24 while the pivotally mounted cylinders 14 automatically swing about their pivots as the plungers 22 are moved outwardly or inwardly. The construction described has the advantage that any desired angular movement of the flap may be obtained for any desired slot adjustment. In this connection it will also be noted that the connection of the flap to the mounting and actuating mechanism does not involve cutting away of any of the nose portions of the flap or in otherwise interfering to any substantial degree with the free passage of air between, or around, the main and auxiliary airfoils.

I claim as my invention:

1. Mechanism for attaching an auxiliary airfoil to a main airfoil and for actuating the auxiliary airfoil, said mechanism including a plurality of arms, each having a hydraulic cylinder and an extensible plunger carried by the cylinder, means for pivotally connecting said plungers to said auxiliary airfoil, means for connecting certain

of said cylinders to said main airfoil so that they are supported against angular movement, means for pivotally connecting other of said cylinders to said main airfoil so that they are free to move angularly, and means for introducing hydraulic fluid into said cylinders to cause said plungers to move said auxiliary airfoil with relation to said main airfoil.

2. Mechanism for attaching an auxiliary airfoil to a main airfoil and for actuating the auxiliary airfoil, said mechanism including a plurality of arms, each having a hydraulic cylinder and an extensible plunger carried by the cylinder, means for pivotally connecting said plungers to said auxiliary airfoil, means for connecting certain of said cylinders to said main airfoil so that they are supported against angular movement, means for pivotally connecting other of said cylinders to said main airfoil so that they are free to move angularly, and means for introducing hydraulic fluid into said cylinders to cause said plungers to extend and lower said auxiliary airfoil, said arms being operative to lower said auxiliary airfoil to substantially the same degree in various extended positions.

FREDRIC E. FLADER.
